UNITED STATES PATENT OFFICE.

HOWARD HINCKLEY, OF WASHINGTON, DISTRICT OF COLUMBIA.

SHOE FOR GOLF-HOLE MARKER-RODS.

1,115,937.

Specification of Letters Patent.

Patented Nov. 3, 1914.

Application filed February 16, 1914. Serial No. 818,957.

To all whom it may concern:

Be it known that I, HOWARD HINCKLEY, a citizen of the United States, residing in the city of Washington, in the District of Columbia, have invented certain new and useful Improvements in Shoes for Golf-Hole Marker-Rods; and I do hereby declare the following to be a full, clear, and exact description of the invention, such as will enable others skilled in the art to which it appertains to make and use the same.

The object of the invention is to provide a novel and efficient form of shoe or protector for the ends of marker rods for golf courses, which rods are normally placed upright in the cups or liners for the golf holes and carry at their upper ends flags or other indicators, which may be seen at a distance to permit the players to locate the various holes in the course. It has been the custom heretofore to use two types of marker rods, the first a bamboo pole carrying a marker flag, the lower end of said pole being provided with a tubular end piece of metal terminating in an elongated spike with a sharp point, which spike passes through a hole in the bottom of the cup. The other type of marker consists of a metal rod of relatively small diameter having its lower end sharpened to pass through the hole in the bottom of the cup. With both types of marker rods, the sharp pointed lower end is objectionable, first because in many cases, it does not afford sufficient bearing between the rod and the cup to hold the rod vertically in a high wind, with the result that the rod oscillates in the wind and mutilates the edge of the earth about the hole rim. A more serious objection to the sharp ended metal rods or elongated metal spikes formed on the shoes for the bamboo rod, is that careless players and caddies are prone to drive the sharp ends into the putting-green when the marker rod is removed, in order to permit the players to putt for the hole, thereby marring the green; and also to remove or replace the marker rod in the cup in such careless manner as to break away and mar the earth about the rim of the hole. The present invention is designed to obviate these difficulties and to provide a shoe which is capable of application to any of the types of marker rods, which shoe is of such form as to prevent mutilation of the turf of the green or the edges of the hole and will, moreover, insure an accurate centering of the rod in

the hole and a firm support to hold the rod in upright engagement with the cup, thereby preventing any lateral whipping motion of the rod under the action of the wind.

The invention is illustrated in the accompanying drawing, in which:—

Figure 1 is a vertical elevation of an ordinary metal marker rod with the shoe attached to the end thereof, and located in normal position in the golf hole cup; Fig. 2 is an enlarged vertical section through the shoe; and Fig. 3 is a corresponding view of the shoe as applied to a bamboo rod or pole.

Referring to the drawings, the shoe proper comprises a tubular body portion 1, preferably made from relatively light sections of metallic tubing, which may be galvanized, which tubular body is closed at its lower end by a plug 2, preferably of metal having a rounded or convex bottom 3 and a tubular tapered neck 4 terminating in an annular shoulder 4', against which the lower rim of the tubular body 1 abuts. Said plug is driven forcibly into the lower end of the body 1 to cause a tight fit between the plug and the body, and to present a smooth joint without projections or sharp edges, as clearly indicated in the drawings. The plug 3 is provided with a central aperture 5, which receives the coned or tapered end of a metal marking rod α , which is then upset or riveted to permanently secure the rod to the shoe.

The upper end of the tubular body 1 is provided with a cap 6 having a pendant flange 7 snugly engaging the upper portion of the body 1, and a crowned top 9 provided with a central orifice formed by forcing the metal at the center of the top downward to constitute a downwardly tapering flange surrounding the central orifice 9, which flange engages the marker rod α and holds the same in accurate vertical alignment with the longitudinal axis of the body 1 of the shoe. When the shoe is applied to a bamboo or wooden rod α' of larger size, the lower end of the rod is placed vertically within the shoe and the space between the rod and the inner walls of the shoe is filled with cement or other appropriate binder to fasten the shoe rigidly to the lower end of the rod, as illustrated in Fig. 3. As thus constructed and applied, the shoe is effective in preventing the turf of the putting-green or the earth about the rim of the cup being marred by careless players or attendants, and is likewise effective in retain-

ing the marker rod in proper normal position in the cup. Moreover, the rounded end of the plug of the shoe materially assists in guiding the rod into the hole in the bottom of the golf cup, especially where the bottom of the cup is made concave or downwardly inclined.

What I claim is:—

1. A shoe for golf hole marker rods comprising a tubular body having a convex end closure.
- 10 2. A shoe for golf hole marker rods comprising a tubular body and a convex ended plug secured in the lower end thereof.
- 15 3. A shoe for golf hole marker rods comprising a tubular body, a convex ended plug secured in the lower end thereof, and a cen-

trally perforated cap on the upper end thereof.

4. The combination with a golf hole 20 marker rod, of a shoe on the lower end thereof comprising a tubular body, a round ended plug secured in the lower end thereof having a perforation in which the rod end is fastened, and a centrally perforated cap 25 on the upper end of the body through which said rod passes.

In testimony whereof I affix my signature, in presence of two witnesses.

HOWARD HINCKLEY.
